UNITED STATES PATENT OFFICE.

LUCY ANN PHILLIPS, OF LUCCA, NORTH DAKOTA.

SKIRT-SUPPORTER.

No. 820,313.

Specification of Letters Patent.

Patented May 8, 1906.

Application filed July 7, 1905. Serial No. 268,678.

To all whom it may concern:

Be it known that I, LUCY ANN PHILLIPS, a citizen of the United States, and a resident of Lucca, in the county of Barnes and State of North Dakota, have invented a new and Improved Skirt-Supporter, of which the following is a full, clear, and exact description.

This invention relates to improvements in supporters for dress-skirts, the object being to provide a supporter of novel and inexpensive construction that may be permanently attached to a corset or like garment and that will firmly hold the skirt in place or closely against the back of the wearer.

15 I will describe a skirt-supporter embodying my invention and then set forth the novel features in the appended claims.

Reference is to be had to the accompanying drawings, forming a part of this specification, in which similar characters of reference designate corresponding parts in all the views

20 Figure 1 is a perspective view of a skirt-supporter embodying my invention, showing the same in position. Fig. 2 shows a portion 25 of a corset with the skirt-supporter thereon. Fig. 3 is a section on the line xx of Fig. 2. Fig. 4 is a vertical section of the device, and Fig. 5 is a perspective view thereof.

It may be here stated that in practice two 30 supporting devices are employed—one at each side of the corset-opening at the back. A description of one, however, will answer for both.

The supporter comprises a plate 1, of suitable material—such, for instance, as metal—and as a means for securing the same to a corset or similar garment I employ a pin consisting of a single length of wire, a portion 2 of which passes along the outer side of the plate, 35 thence through an opening near one end thereof and formed in a coil 3 at the inner side of the plate, and from this coil the pin portion 4 extends. At the opposite end the portion 2 of the wire is extended through an 40 opening in the plate and is turned to form a hook or keeper 5 for the pin. The skirt-engaging device consists of a single length of wire having a portion 6 extending along the front of the plate and then extending inward 45 through openings in the plate and downward at the inner side of the plate, as indicated at 7, thence through openings in the plate, and turned upward to form hook members 8 at the front of the plate.

In use the supporting devices will be secured to the corset as indicated clearly in Fig. 2. The shirt-waist may be engaged with the hook members 8, and then the hook members are to be passed through the waistband of the skirt, and to prevent possible scratching of the wearer's hands or the hook portions from engaging with other devices a belt 9 may be worn over the hook portions. 55

Having thus described my invention, I claim as new and desire to secure by Letters 60 Patent—

1. A skirt-supporter, comprising a plate having a pin on its rear face for securing it to a garment and provided with two pairs of openings below the pin, and a piece of wire 70 passed through the upper pair of openings from front to rear, then bent downward along the rear face of the plate and then passed through the lower pair of openings and having its terminals bent outwardly and upwardly to form hooks on the front face of the plate. 75

2. A skirt-supporter, comprising a plate having means for securing it to a garment and provided with two pairs of openings below 80 the securing means, and a piece of wire passed through one pair of openings, then bent to extend vertically along the rear face of the plate and then passed through the other pair of openings and having its terminals bent outwardly and upwardly to form hooks on the front face of the plate. 85

3. A skirt-supporter comprising a plate, a single length of wire having a portion extended along the front of the plate, thence 90 through the plate and formed in a coil terminating in a pin member, the other end of said wire also being extended through the plate and formed into a keeper for the pin member, another length of wire having a portion extended along the front of the plate, thence 95 having portions passing through the plate and downward at the inner side thereof, thence outward and upward, forming skirt-engaging hook members. 100

In testimony whereof I have signed my name to this specification in the presence of two subscribing witnesses.

LUCY ANN PHILLIPS.
